ELONGATED POT BURNER AND FLAME RING

Carl S. Greer, Jr., Albion, Mich., assignor to
Lonergan Manufacturing Company, Albion,
Mich., a corporation of Michigan

Application July 5, 1947, Serial No. 759,194

3 Claims. (Cl. 158—91)

1

This invention relates to a new and improved vaporizing type burner for liquid fuel and has for an object the provision of an improved construction capable of safe and economical operation over a wide range.

An object of the invention is to provide a simple and efficient form of vaporizing pot adapted to burn economically at all stages of operation.

A further object of the invention is to provide a vaporizing pot of elliptical or oval shape having primary and secondary air inlet openings in the side walls whereby to make the vaporizing pot thinner from front to back, and its side wall curved at all points to feed jets of primary air in converging streams toward the center of the pot, the flame thus being produced having a greater heat radiating surface to effect maximum liberation of heat in a highly efficient manner.

Another object of the invention is to provide in a vaporizing pot of the type disclosed a flame opening in the flame plate of different contour than the pot itself, the portion on opposite sides of the major axis at the ends of the flame opening being cut back to relieve congestion of air streams at these ends and provide for uniform flow upward, thereby eliminating eddy currents within the pot.

Other objects and advantages of the invention will be apparent from the following detail specification when taken in connection with the accompanying drawings in which:

Fig. 1 is a cross sectional view of a heater embodying the present invention;

Fig. 2 is a top view of the vaporizing pot illustrating the flame plate and the contour of its flame opening;

Fig. 3 is a cross sectional view taken on line 3—3 of Fig. 2 looking in the direction of the arrows; and

Fig. 4 is a similar view but taken on line 4—4 of Fig. 2 looking in the direction of the arrows.

The heater illustrated in the drawings is what is commonly called a space heater. It will be understood, however, that this heater may be of any other type and that the invention may be incorporated in central heating units, furnaces generally, stoves, etc. As illustrated, the heater comprises a housing 1, a supporting frame 2, a combustion chamber 3 and a burner chamber 4. The burner chamber 4 is disposed in pot 5 supported in any suitable way in housing 1, this depending upon the design of the housing and the type of heater in which this pot 5 is used.

It is found that a more efficient form of flame is produced if it has a maximum heat radiating

2

surface. To obtain this maximum heat radiating surface, pot 5 is made elliptical or oval in shape which also decreases the dimension of the heater from front to back, this being advantageous in that the heater will occupy less space in that direction and can be placed closer to the wall and thus fitted into spaces not otherwise accommodating a heater. Side wall 6 is provided with uniformly spaced groups of air inlet openings. These groups of air inlet openings are disposed at different levels, the primary air inlet openings 7 being located in rows below the secondary air inlet openings 8. If the side wall 6 is sheet metal, these air inlet openings may be formed therein before the wall is formed, but, irrespective of how the wall is formed, they may be substantially uniform in size and spacing. The bottom 9 may be a cast metal or sheet metal pan with a well 10 substantially centrally provided and a trough 11 leading thereto from one side of the pot. As illustrated, oil line 12 will connect at 13 to supply oil at a controlled rate to trough 11 by a suitable metering device 14.

Within the burner chamber 4 is provided two accumulator segments or elements 20 and 21 arranged to embrace a number of primary openings 7, and, while only those of the lower row are illustrated as included, it will be understood that openings of other rows might also be included. These accumulator elements constitute the subject matter of copending application Serial No. 759,193, filed July 5, 1947, and is claimed therein. They are specifically shown herein as substantially U-shaped, each with a top wall 22 and with side walls 23 and 24, and are seated upon bottom 9 in opposing relation against the side wall 6 of the pot. The inside edges of these top and side walls of each accumulator element may be cut somewhat arcuate to conform to the shape 46 of the side wall 6 of the pot.

One of the accumulator elements, say element 20, is provided with an area enclosed on three sides to form a vaporizing or pilot chamber 25. This chamber 25 may have its side walls 26 perpendicular to the bottom 9 and be integrally connected to top wall 22 of accumulator element 20. A top wall 27 may span side walls 26 in integral relation and slope somewhat downwardly so that the lower inner edge will be below the lower row 50 of the primary air openings 7 and the upper edge will be above these openings whereby the latter will communicate with this vaporizing chamber 25 and supply air thereto. It will be noted in Fig. 3 that additional openings 14' have been 55 furnished in the lower row of openings 7 to com-

municate with vaporizing chamber 25 so that the necessary volume of air to assure a proper mixture at low or pilot flame with minimum fuel consumption at this stage without formation of smoke or carbon will be obtained.

The supply of liquid fuel to the burner chamber 4 may be controlled by suitable adjustment of metering device 14. The liquid fuel entering at 13 will vaporize and form a combustible mixture and burn at low or pilot flame at and slightly to the rear of the forward edge of top wall 27 of the vaporizing chamber 25. At this stage of operation, a minimum consumption of oil takes place, and, in actual operation, it is found that the arrangement of the parts provides for a consumption as low as 1 cc. of oil per minute without smoke or carbon being produced. The flame may continue to burn at a low pilot stage indefinitely with a clear smokeless appearance and the mixture will be adequate to effect complete combustion. By increasing the supply of liquid fuel, the pilot flame will increase until the flame either is held at intermediate stage, which is within the zone defined by the space between accumulator elements 20 and 21 and in the vicinity of their top walls 22, or is permitted to rise in burner chamber 4 until it burns at and above opening 17 in flame plate 15 where combustion is then completed in combustion chamber 3 at high fire stage.

Accumulator elements 20 and 21 serve to direct the air entering the primary air inlet openings 7 embraced by these elements to the space therebetween to mix with the vaporizing oil rising from well 10. The combustible mixture at intermediate fire will burn in this space slightly above or at the level of top walls 22 and consume at this stage, say between 6 and 8 cc. of liquid fuel per minute, without the flame smoking or producing carbon. Accumulator elements 20 and 21 will direct a uniform flow of air forwardly and prevent undesirable eddy currents. As the fuel supply increases, the level of the flame will increase so that the air supplied by the upper primary air inlets 7 will mix with the vaporized fuel to provide a completely combustible mixture. With the flame at opening 17 and burning in combustion chamber 3, the secondary air inlets 6 will supply additional air to the mixture and assure complete combustion, the flame at this high stage consuming between 35 and 45 cc. of liquid fuel per minute.

The shape of pot 5 is preferably elliptical or oval and side wall 6 is curved at all points. This will make pot 5 thinner from back to front which I find is advantageous in the construction of heaters of this type because the space to be occupied by them with respect to the distance or projection from the wall will be less, and these heaters may be used therefor in many places where limited space has otherwise restricted their use. With side wall 6 curved at all points and elliptical, the primary air inlet openings 7 will feed jets of primary air in converging streams toward the center of pot 5. The contour of flame opening 17 in flame plate 15 is different from the contour cross-sectionally of pot 5. Instead of making flame opening 17 an ellipse charted along the same axes as the ellipse of pot 5, the portions on opposite sides of the longitudinal axis of opening 17 are cut away, this being indicated at 30, so that the opening 17 becomes somewhat larger at the ends. It is found that cutting away the corners of opening 17 at 30 relieves congestion of the mixture or air streams at

these ends in burner chamber 4 and provides for uniform flow upwardly, thereby eliminating eddy currents within the pot.

The contour of flame opening 17 further provides for an efficient form of flame within combustion chamber 3. This flame will spread and while opening 17 is not elliptical the flame will assume a form approaching the shape of combustion chamber 3 and will present a greater flame surface for heat radiation than other shapes of heaters. It will be remembered that it is advantageous to burn the mixture in a flame having some body thickness thereto to assure complete combustion and prevent the escape of unburned gases. Failure of the secondary air to mix thoroughly with the hydrocarbon molecules will cause products of combustion in the form of soot and carbon. The burner herein disclosed will burn the mixture completely in the combustion chamber 3 at high flame. With congestion of the air streams and combustible mixture relieved within burner chamber 4, the flow through this chamber will be smooth and uniform to produce an efficient flame.

It is also found that accumulator elements 20 and 21 disposed in opposed relation on opposite sides of the major or longitudinal axes of both the pot 5 and the flame opening 17 in cover 15 became particularly useful in the general arrangement of the parts described. These accumulator elements have a straight front edge which will have the space therebetween somewhat of the same general shape as the flame opening 17 so that there will be a tendency of the mixture or rising vapors mixing with the streams of primary air, in burner chamber 4 to assume a body of corresponding formation and thus produce a flame having a contour of substantial flame surface for heat radiation. Not only will there be maximum heat liberation but the flame will burn clean and will not smoke or cause soot.

Without further elaboration, the foregoing will so fully explain the gist of my invention that others may, by applying current knowledge, readily adapt the same for use under varying conditions of service, without eliminating certain features, which may properly be said to constitute the essential items of novelty involved, which items are intended to be defined and secured to me by the following claims.

I claim:

1. A liquid fuel burner comprising an open topped burner pot of elliptical shape cross-sectionally having a bottom wall, a side wall and a series of upper and lower air inlet openings circumferentially disposed in said side wall to give a substantially uniform supply of air to the pot, fuel supply means for delivering a regulatable quantity of fuel to said pot, and a flame plate 55 at the top of said pot having an elongated flame opening therein, said flame opening being disposed centrally in said flame plate and having its ends on opposite sides of its longitudinal axis a distance closer to the side wall of said pot than other portions of said flame opening.

2. A liquid fuel burner comprising an open topped burner pot elongated cross-sectionally and having a bottom wall, a side wall and a flame plate at the top thereof, fuel supply means for 60 delivering liquid fuel to said pot, air supply means for delivering a substantially uniform supply of air to said pot to mix with the vaporized liquid fuel, said flame plate having a flame opening 65 therein, said flame opening also being elongated with its ends on opposite sides of the longitudinal

axis being a distance closer to said side wall of the pot than the other portions of said flame opening.

3. A liquid fuel burner comprising an open topped burner pot of elongated cross-section and having a bottom wall, a side wall and a flame plate at the top thereof, fuel supply means for delivering liquid fuel to the bottom of said pot, there being air inlet openings disposed circumferentially in said side wall, said side wall being curved at all points circumferentially to cause said air inlet openings to feed jets of air in converging streams substantially toward the center of the pot and give a substantially uniform supply of air to the pot, said flame plate being pro-

vided with an opening therein having substantially the same axes as the burner pot with its ends at opposite sides of the major axis a distance closer to said side wall than the other portions of said flame opening.
